UNITED STATES PATENT OFFICE.

EDWARD HUBER AND FREDERICK STROBEL, OF MARION, OHIO.

GRAIN THRASHING AND SEPARATING MACHINE.

SPECIFICATION forming part of Letters Patent No. 250,248, dated November 29, 1881.

Application filed June 2, 1881. (Model.)

To all whom it may concern:

Be it known that we, EDWARD HUBER and FREDERICK STROBEL, of Marion, in the county of Marion, and in the State of Ohio, have invented certain new and useful Improvements in Grain Thrashing and Separating Machines; and we do hereby declare that the following is a full, clear, and exact description thereof, reference being had to the accompanying drawings, and to the letters of reference marked thereon, making a part of this specification.

This invention relates to certain improvements in grain thrashing and separating machines; and it has for its objects to provide an apparatus whereby the grain may be more thoroughly separated from the straw and rubbish than heretofore. This object we attain by the apparatus illustrated in the accompanying drawings, in which—

Figure 1 represents a side elevation of our apparatus complete; Fig. 2, a longitudinal vertical section thereof; Fig. 3, a rear elevation; Fig. 4, a detached perspective view of a portion of the main shoe and grain-discharge chute; Fig. 5, a detached view of a portion of the stacker; Fig. 6, a transverse sectional view of the stacker; Fig. 7, a detached perspective view of the braces which in part support the main shoe of the apparatus; and Fig. 8 is a detached view of the concave-adjuster shaft.

The letter A indicates the frame of the apparatus, which is constructed of wood or other suitable material.

At the forward end of the apparatus is located the usual thrashing-cylinder, the journals of which have their bearings in suitable boxes at the sides of the machine.

The letter B indicates a concave-adjuster, which is adapted to work in connection with the thrashing-cylinder, to control the admission of grain to the machine. The said adjuster consists of the two pivoted arms C, one secured to each side of the apparatus, and a transverse shaft, D, extending through the sides of the apparatus and provided with eccentrics E, which work between parallel guides F, attached to the frame. The said shaft is provided with a ratchet, G, which is controlled by means of a pawl, H, secured to the frame of the apparatus.

The letter I indicates a horizontally and lon-

gitudinally vibrating floor or bottom, which is supported on the link K, pivoted to the frame of the machine in such manner that it may move freely in a longitudinal direction.

The letter L indicates the main driving-shaft of the apparatus. This is provided with cranks M, which connect by the pitmen N with the vibrating floor or bottom I, by means of which a reciprocating motion may be imparted to said bottom.

The letter P indicates an inclined riddle, which extends from the forward end to about the center of the apparatus, above the reciprocating bottom. The said riddle, at its forward ends, is supported by the pivoted links R, and at its rear ends is secured to the upper ends of the levers S, fulcrumed to the frame of the apparatus. The lower ends of said levers have pivoted to them the forward ends of a rear riddle, T, the ends of which are supported by the pivoted links U in a manner similar to the forward riddle. The letter V indicates a comb located at the rear end of the forward riddle. The rear riddle is located directly over the main shoe and riddle A'. This latter is supported from the frame of the apparatus by means of the braces B' and springs C' in such manner that it may oscillate freely laterally. The said shoe receives its motion through the medium of a vertical rock-shaft, D', which connects, by a rod, E', with one of the pitmen N, the lower end connecting by means of an arm, F', with a rod, G', secured to the shoe.

The letter H' indicates a "rubbish-rack," constructed of slats, somewhat like a slatted window-shutter, and arranged directly over a ridge, K', in shoe A'. The said rack H' is suspended by links I' I', and connected by means of springs K' with the pitman N, by means of which the rack is shaken independently of the shoe A'. The rack H', combined, as shown, with the main shoe, the riddle, and the vibrating bottom, swung independently of each other, is not designed to serve as a riddle nor as an extension of the straw-racks, but as a third rack to carry off the coarser rubbish and straw working through the two upper racks.

The letter L' indicates a reciprocating bottom, supported on links M', pivoted to the frame of the apparatus. The said bottom is

connected with one of the pitmen N by means of a rod, P', whereby a reciprocating motion is given to said bottom.

The letter R' indicates a grain-chute located at the forward end of the shoe A', immediately below the same. The said chute is supported upon swinging links S', pivoted to a cross-bar, T', which is suspended by links U', pivoted to the frame of the apparatus. By turning the links S' a quarter of a revolution in either direction the grain-chute may be caused to deliver grain to either side of the apparatus.

The letter V' indicates the stacker. This may be of the ordinary description. The sides are raised, as indicated by the letter W', by thickening the bottom at such parts to prevent the belt from wear.

At the tail of the apparatus is located a hinged comb, A², below which is arranged a removable extension, B², which can be detached when the apparatus is not in use, so as to prevent water, in the case of rain or storms, from finding its way and running down into the machine from the tail thereof.

The springs C' have rectangular heads B³, which are secured to the inclined bearings B⁴ in such manner that the blades of the springs will be in line with the front pivot of the shoe.

The chute R' receives a vibratory transverse motion through the medium of a rod, C², connecting with a vertical rock-shaft, D², which connects, in turn, by means of a rod, E², with one of the pitmen N, from which it derives its motion.

Having thus fully described our invention, 35 what we claim, and desire to secure by Letters Patent, is—

1. The combination, in a grain-separator, of the concave of the thrashing-cylinder, the pivoted arms C, a transverse shaft, D, the eccentrics E on this shaft, the guides F on the frame, a ratchet-wheel, G, on said shaft, and a pawl, H, all substantially as described. 40

2. The combination, with the grain-chute R', of the jointed supporting-links S', the cross-bar T', and the suspension-links U', whereby the chute can be inclined to the right or left and given an endwise shaking motion, substantially as described. 45

3. The combination of the bottom L', the comb A², hinged to the main frame above the extension of bottom L', and the riddle T, having its tail end arranged above the jointed end of the comb, substantially as described. 50

4. The combination, with the shoe A', of the supporting-braces B', pivoted at their convergent ends, and the suspension-springs C', having their flat blades in planes radiating from the pivot of the said braces, substantially as described. 55

In testimony whereof we affix our signatures, in presence of two witnesses, this 29th day of April, 1881.

EDWARD HUBER.
FRED. STROBEL.
